UNITED STATES PATENT OFFICE.

CHARLES C. WRIGHT, OF CAMDEN, NEW JERSEY.

ATTACHMENT FOR TELEPHONES.

1,122,347.

Specification of Letters Patent. Patented Dec. 29, 1914.

Application filed February 9, 1914. Serial No. 817,578.

To all whom it may concern:

Be it known that I, CHARLES C. WRIGHT, a citizen of the United States, residing at Camden, in the county of Camden and State of New Jersey, have invented certain new and useful Improvements in Attachments for Telephones; and I do declare the following to be a full, clear, and exact description of the invention, such as will enable others skilled in the art to which it appertains to make and use the same.

This invention relates to improvements in telephones and more particularly to attachments therefor which are designed to prevent the accumulation of disease germs in the mouth pieces thereof.

The primary object of the invention is to produce a simple and efficient device of the character described which may be readily formed of any suitable material but which is preferably stamped out of sheet metal.

A secondary object is to provide efficient means for securely holding the usual antiseptic paper over said mouth piece.

With the above objects in view the invention resides in certain novel features of construction and combination herein described and claimed and shown in the drawings wherein:

Figure 1 is a side view showing the application of my invention to the mouth piece of a telephone; Fig. 2 is a rear elevation of the mouth piece removed from the phone; Fig. 3 is a front view thereof; Fig. 4 is a longitudinal section showing the invention applied; and Fig. 5 is a horizontal section taken on the line 5--5 of Fig. 3.

In the accompanying drawings, I have shown my improved attachment as comprising a front plate 1, rear plate 2, a third plate 3 which is hingedly connected to the front plate 1 and a paper reel 4.

The front and rear plates 1 and 2 may be constructed of any suitable material but are preferably formed of a single piece of sheet metal which is bent substantially upon itself to provide an arch plate 5 which rigidly connects said plates and is provided on its opposite ends with upstanding integral ears 6.

The front plate 1 is provided with an opening 7 which is of a size to register with the open outer end of the mouth piece M when said plate is in position as is shown in Fig. 1. When in this position, a pair of

resilient fingers 8 which are formed integrally with the rear plate 2 are adapted to be held in contact with the body of the mouth piece M by a screw 9 which passes loosely through the free end of one of said fingers and is threaded into the free end of the other finger, a lug 1' struck inwardly from the plate 1 underlying the outer end of said mouth piece as clearly shown. By this arrangement, the entire device is securely held upon the phone in the above described manner.

The plate 3 has an opening 10 which is preferably of the same size as the opening 7 and disposed in direct alinement therewith. The hinged connection between the plates 1 and 3, before mentioned, is formed by striking integral knuckles 11 from the plate 1 and similar knuckles 12 from the plate 3, a pintle 13 being passed through said knuckles. Opposite this hinged connection the plate 3 is provided with a rearwardly extending spring catch 14 which is struck out of the same piece of metal as said plate and is adapted to normally snap around one edge of the plate 1 and thus secure the plate 3 in operative position.

The paper reel 5 is here shown in the form of a solid roller whose pintles 15 are removably mounted within bearing openings 16 formed in the upright ears 6, the metal forming said ears, being bent slightly outward from said openings 16 to the rear of said ears as at 17 to provide suitable guides for facilitating the engagement of the pintles 15 with the openings 16.

With the parts as above described, a strip S of antiseptic paper is adapted to be rolled upon the reel 4 and the plate 3 is then swung open upon its hinge, whereupon said paper may be brought downwardly in front of the plate 1 where it will overlie the opening 7 therein and the open outer end of the mouth piece M. When in this position, the plate 3 may be again closed and its spring catch 14 is engaged with the edge of the plate 1 as before stated. This action will securely clamp the strip of paper S between the plates 1 and 3 and will prevent the removal thereof until said plate 3 is again swung open.

By the above described construction, it will be seen that I have produced a very simple and efficient device of the character described which will effectually prevent the entrance of any disease germs into the

mouth piece M to which it is applied. The germ destroying qualities of the paper strip S are of such strength as to render them effective for predetermined periods of time, 5 after which periods, the front plate 3 is swung outwardly, the paper is pulled down so that a new working area is provided, the plate 3 is then again closed and the portion 10 of the strip S which has been previously in use, is torn off and destroyed.

Although I have shown the paper reel 5 as located at the top of the attachment it will be readily understood that it would operate to equal advantage were it disposed on 15 either side or the bottom thereof.

From the foregoing description taken in connection with the accompanying drawings, the construction and operation of the invention will be readily understood without requiring a more extended explanation. 20

Various changes in the form, proportion and minor details may be resorted to without departing from the spirit of the invention as claimed.

Having thus described my invention, 25 what I claim as new and desire to secure by Letters Patent is:—

1. In a device of the character described, a front and rear plate connected on one of 30 their edges, the front plate having an opening adapted to register with the open end of the mouth-piece of a telephone, resilient fingers depending from said rear plate and adapted to embrace the body of said mouth-piece, a projection on said front plate adapted 35 to underlie the outer end of said mouth-piece, a third plate hingedly connected to one edge of said front plate and having an opening registering with the opening in said

front plate, a paper reel from which paper 40 is adapted to pass between said front plate and the plate hinged thereto and a catch for holding said hinged plate and said front plate in contact with said paper.

2. A device of the character described 45 comprising a front and rear plate formed by bending a flat piece of material substantially upon itself, the front plate having an opening adapted to register with the open end of a telephone mouth-piece, integral 50 spring fingers depending from said rear plate and adapted to yieldingly embrace the body of said mouth-piece, a screw passing loosely through the free end of one of said spring fingers and threaded into the free 55 end of the other finger, a projection struck inwardly from said front plate and adapted to underlie the outer end of said mouth-piece, integral resilient bearing ears rising from the portion of said piece of material connecting said front and rear plates, a paper 60 reel revolvably mounted between said ears, the paper therefrom passing over the opening in said front plate, an apertured plate hingedly connected to said front plate and 65 adapted to swing in front thereof and an integral spring catch on said hinged plate and adapted to yieldingly engage one edge of 70 said front plate and retain said paper in position.

In testimony whereof I have hereunto set my hand in presence of two subscribing witnesses.

CHARLES C. WRIGHT.
